DESK TYPE DRAFTING MACHINE

Lewis G. Webster, Dayton, Ohio

Application September 29, 1943, Serial No. 504,244

2 Claims. (Cl. 33—79)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to drafting machines, and particularly, to a novel attachment for mounting a drafting machine on the surface upon which a drawing is to be made.

An object of the invention is to provide a device which may be used in connection with a pantograph type of universal drafting machine of more or less conventional design, and which, when so used, will greatly extend the scope and utility of a machine of this character.

Another object is to so construct and arrange the attachment that a drafting machine of this type which has been provided therewith may be secured to, and used on, a wide range of drawing surfaces, from a smooth sheet metal surface to a soft and more or less uneven pine drawing board, and from a plane surface to one which is more or less uneven or which is slightly curved.

I attain these and other objects and advantages by the improvement hereinafter described and shown in the drawings, wherein,

Fig. 1 is a top plan view of a pantograph type universal drafting machine of more or less conventional design except that it is provided with my novel attachment for securing it to a drawing surface. Fig. 1 shows the attachment in its simple form.

Fig. 2 is a vertical section through the attachment, taken on this line 2—2 of Fig. 1, showing alternate forms of mounting means.

Fig. 3 is a top plan view showing an arrangement similar to that shown in Fig. 1 except that certain additional adjusting means are provided for extending the range of its applicability and its effectiveness in operation.

Fig. 4 is a side elevation of the attachment, viewing Fig. 3 in the direction of the arrow 4.

Fig. 5 is a cross section taken on the line 5—5 of Fig. 3, showing the construction of the adjusting means.

Like reference characters refer to like parts throughout the several views.

Referring now more particularly to Fig. 1, a conventional pantograph type of universal drafting machine 10 comprises the usual linearly graduated right angle ruling piece comprising two blades 12, pivoted at 14 to the protractor head 16 having circumferential graduations 17.

A clamp screw 18 will fix the ruling piece 12 in any angular position to which it may be turned. Two ears 20 are carried by the head 16 for the

spaced apart pins 22, by which the parallel links 24 are hinged to the head, the links, at their other ends, being equally spaced apart on a joint member 26 by hinge pins 28.

Two hinge pins 30, carried by the joint member 26, are provided for pivotally supporting the lower ends of the parallel links 22, the upper ends of the links being similarly supported by hinge pins 33, which may be carried by a pivot plate 34. The pivot plate 34, when made as in common practice, is usually provided with some form of clamping means for securing it permanently to the drawing board or other surface upon which a drawing is to be made or upon which layout lines are to be inscribed.

Thus far, the drafting machine above described is conventional, my improvements, which may be broadly designated by the numeral 35, and which are the subject of this invention, residing in the provision of improved attachment for more flexibly and advantageously positioning the drafting machine on any of the several kinds of surfaces hereinbefore mentioned.

The improved attachment 35 has a base member 36 which may preferably be made to the contour shown of any suitable moldable material. A knob 38 for lifting the base when moving it to different positions may be secured thereto by a screw 40. A double jointed hinge 42 is composed of three parts 44, 46 and 48, hinged together by pins 50 and 52. Hinge part 44 is secured to the underside of the base member 36 by screws 54, while hinge part 48 is secured to the conventional drafting machine pivot plate 34 in any suitable manner. Obviously, parts 34 and 48 may quite easily be made integral, but it is noted that, for purposes of description, the pivot plate 34 will be considered as part of the conventional drafting machine 10 while the hinge part 48 will be considered as part of my improved attachment, whether the parts 34 and 48 are made separately or integral.

Feet 56 are each provided with a threaded part 58 which may be screwed into the underside of the base 36, the lower parts being provided with vacuum cups 60. An additional set of feet 62 having like threaded parts 58 are provided on the underside with pins 64. If the surface upon which the work is to be done is hard and smooth, the feet 56, having the vacuum cups 60, are preferably used, while if the surface is somewhat uneven and its material soft, the feet 62, having the pins 64, are preferably employed. Furthermore, if the surface upon which a layout is to be accomplished is somewhat uneven or curved, either

convex or concave, the double joint hinge 42 will allow both the drafting machine 10 and the attachment 35 to substantially conform to the curved surface. If the protractor graduations 16 are set to the zero line and one of the edges 12 set to a reference line before the feet are pressed down to affix them to the surface, the protractor graduations 16 will register correctly for laying off further angles.

The structure above described with reference to Figs. 1 and 2 disclose the basic principle of my improvement. The device shown in Figs. 3, 4 and 5, however, disclose certain refinements which add to its advantages and further extend its usefulness.

In the modification of Figs. 3, 4 and 5, the same conventional pantograph type of universal drafting machine 10 is employed, and the same vacuum cup feet 56 and pin feet 62 are provided and attached in the same manner. The double joint hinge 66 is similar to the hinge 42 disclosed in Fig. 1 except that, instead of being attached in fixed position, the hinge 66 has its longer leaf 68 pivotally supported on the base 10 by a hinge screw 72, while an adjusting screw 74, which may be fixed in the long hinge leaf 68, extends upwardly through an arcuate slot 76 in the base and has the upper end threaded and provided with the adjusting nut 78.

A light spring 80 may be incorporated in one of the hinge joints, as shown, for preventing too great a drag by the drafting machine arm on the working surface. The action of the spring 80 is particularly beneficial when drawing layout lines on a convex surface, in which the surface 35 upon which the base 35 rests and that upon which the drafting machine 10 rests are not in precisely the same plane. In such a case, the spring will help raise the upper ends of the links 32 so that the blades 12 may conform more closely to the surface.

Where the double hinge 66 is pivotally attached as in Fig. 3, the device may preferably be located on the drawing surface by first setting the blade member 12 to zero on the protractor graduation 17, if it is not already there, then bringing the blade member 12 approximately to a reference line, then fixing the base member 56 to the surface with the vacuum cups 60 or with the pins 64, as the case may require. Minor adjustments to bring the blade member 12 accurately to the reference line, above mentioned, may preferably be made by loosening the adjusting nut 78 and swinging the drafting machine 10 about the pivot screw 72. By following this procedure, the blade member 12 is still at zero of the protractor graduations 17 when it is finally aligned with the reference line, so that angles which are to be laid out from the reference line or any line parallel thereto may be set up directly on the protractor graduation 17.

Pivoting the hinge 66 also has the advantage that the base 10 may be moved around to avoid obstructions in the surface, then affixed where convenient, and the machine afterward be brought to the desired position by swinging it on the pivot 72.

Other advantages are as follows:

Any available portion of a bench or desk top may be used for making a drawing, and the drafting machine may be located in the most convenient place with respect to this available drawing space.

Views in remote corners of large drawing boards, which are ordinarily difficult to reach with a fixed drafting machine, may readily be reached with my improved device by shifting the base to the most convenient location.

Angular projections are more easily and accurately made with the device, since the entire device may be shifted to the angle of the projection with the protractor remaining at zero, and lines at an angle with the angle of the projection read directly on the protractor. Where the pivoted hinge of Figs. 3 to 5 are employed, the device need be, in the first instance, placed only at an angle approximate the projected angle, then, with the protractor still at zero, the ruling blades may be accurately adjusted to the projected angle by means of the nut 78.

The device is most advantageously used for laying out guide lines for cutouts and for bending on sheet material such, for instance, as when cutting an access door in the skin of an airplane, or for layout work on the surface of any other large flat or somewhat curved body which cannot readily be brought to a drawing board and affixed thereto.

Having described my invention, I claim:

1. In a pantograph type of universal drafting machine, having a base for securing said drafting machine to a working surface, vacuum cup means on said base for securing said base to any part of the working surface, and a hinge structure connecting said base to said machine comprising a first hinge part, hinge means for adjusting said first hinge part with respect to said base about a vertical axis, means to hold said first hinge part in the adjusted position, a second hinge part fast on said machine, a third hinge part joining the first and second base parts, and two hinge pins joining the three hinge parts to each other, the two hinge pins being substantially parallel to each other and to the working surface.

2. In a pantograph type of universal drafting machine having a base for securing said drafting machine to a working surface, vacuum cup means on said base for securing said base to any part of the working surface, and means connecting said base to said machine which includes a hinge for adjusting said machine about a vertical axis with respect to said base.

LEWIS G. WEBSTER.
